UNITED STATES PATENT OFFICE.

WILLIAM H. ROWE, OF LOS ANGELES, CALIFORNIA.

ACETYLENE-GENERATOR.

1,285,799.

Specification of Letters Patent. Patented Nov. 26, 1918.

Application filed May 20, 1918. Serial No. 235,716.

To all whom it may concern:

Be it known that I, WILLIAM H. ROWE, a citizen of the United States, residing at Los Angeles, in the county of Los Angeles 5 and State of California, have invented new and useful Improvements in Acetylene-Generators, of which the following is a specification.

My invention relates to an acetylene generator and consists of the novel features herein shown, described and claimed.

One of the principal objects of my invention is to make a gas operated motor for feeding the carbid and to regulate the motor 15 automatically by the gas pressure.

Figure 1 is a top plan view of an acetylene generator embodying the principles of my invention looking in the direction indicated by the arrow 1 in Fig. 2.

Fig. 2 is a side elevation looking in the direction indicated by the arrow 2 in Fig. 1.

Fig. 3 is a fragmentary vertical central section of the gas control switch for regulating the motor taken on the line 3-3 of 20 Fig. 1.

Fig. 4 is a vertical section of the motor taken on the line 4-4 of Fig. 2.

Fig. 5 is a fragmentary vertical sectional detail taken on the lines 5-5 of Figs. 1 30 and 2.

Fig. 6 is a horizontal sectional detail taken on the line 6-6 of Fig. 5.

A generating tank 1 is circular in plan and has a dished bottom 2 provided with a 35 drain pipe 3 leading from its lowest point, the flow through the pipe being controlled by a stop cock 4. A rim 5 extends downwardly in line with the wall of the tank 1 to hold the bottom 2 elevated. An agitator 40 6 is mounted horizontally in the tank 1 to be operated by a crank 7. The agitator 6 consists of a shaft 8, arms 9 extending from the ends of the shaft and blades 10 connecting the arms; said blades 10 being 45 curved on their outer faces to fit closely the inner face of the bottom 2.

A filling funnel 11 is connected to a pipe 12 which extends downwardly from the bottom of the funnel and then laterally through 50 the wall of the tank 1 at its upper end, there being a stop cock 13 to control the passage through the pipe 12 so that by opening the stop cock 13 water may be poured into the funnel 11 to fill the tank 1 to the desired 55 extent.

A gas dome 14 extends upwardly from the

tank 1 and is built upon the tank 1, there being a flanged wall 15 connecting the lower edge of the vertical wall of the dome 14 to the upper edge of the vertical wall of the 60 tank 1, so as to make the dome considerably smaller in plan than the tank. A pressure gage 16 is tapped into the dome 14 at one side, a safety valve 17 is connected through the wall of the gas dome 14 near the top 65 of a gas chamber 18, said safety valve being provided with a cap 19 held in place by a padlock 20 so that the valve can not be tampered with without removing the padlock. A pipe 21 connects the valve casing to the 70 chamber 18 through the wall 14, and a pipe 22 extends downwardly from the valve casing to a T 23. A U-shaped trap 24 extends downwardly and upwardly from the T 23, a blow-off pipe 25 extends upwardly from 75 a T 26; said T 26 being on the opposite end of the trap 24 from the T 23. A pipe 27 connects the T 23 to a chamber 28 within the tank 1, the passage through the pipe 27 being controlled by a stop cock 29 and a 80 drain pipe 30 leads horizontally from the T 26.

When it is desired to clean out the tank 1 and start the generator to operating, the stop cock 4 is opened and the stop cock 13 85 is opened, water poured into the funnel 11 and allowed to run into the tank 1 and out through the pipe 3 to wash out the old material, then the stop cock 4 is closed and the tank 1 filled with water until the water 90 overflows through the pipe 30, and then the stop cock 13 is closed, the trap 24 will be full of water and the depth of the trap is sufficient to hold the desired gas pressure. The stop cock 29 may be closed and the 95 safety valve 17 regulated to the desired gas pressure and then a surplus of pressure will open the safety valve 17, blow gas through the pipe 22, through the trap 24 and through the blow-off pipe 25 or the drain pipe 30, 100 until the surplus pressure has been reduced. A cap plate 31 is bolted to an angle flange 32 and the angle flange is rigidly fixed upon the upper end of the gas dome 14. Before the cap plate 31 is applied, a carbide hopper 105 33 is centrally located within the vertical wall of the gas dome 14; said hopper having a flange 34 extending outwardly around its upper edge to rest upon the upper edge of the dome 14. A man hole construction 35 110 provides access to the hopper 33 for inserting the carbide 36. A feed plate 37 is hori-

zontally suspended below the hopper 33 by straps 38; said feed plate being circular in plan and located a short distance below the outlet 39 of the hopper. A feed shaft 40 is 5 mounted vertically through the center of the cap plate 31, there being a stuffing-box construction 42 around the shaft and the lower end of the feed shaft 40 is rotatably mounted through the center of the 10 feed plate 37, there being blades 43 and 44 fixed upon the shaft 40 and swinging upon the upper face of the feed plate 37, so that when the shaft 40 rotates the blades 43 and 44 will swing to move the carbid outwardly 15 and discharge it upon the periphery of the feed plate 37. The front faces of the blades 43 and 44 are winding backwardly relative to a radial line so as to continuously advance the carbid toward the rim of the feed 20 plate by the rotation of the blades.

A worm gear 45 is fixed upon the upper end of the shaft 40 above the cap plate 31, a shaft 46 is mounted in bearings 47 on top of the cap plate 31 and carries a worm 48 in mesh with the gear 45. The shaft 46 extends beyond the edge of the cap plate 31 and a pulley 49 is fixed upon the outer end of the shaft. A belt 50 connects the pulley 49 to a pulley 51 fixed upon a shaft 52 of 25 a gas motor 53, a pipe 54 leads outwardly from the upper part of the chamber 18 through the dome 14 and an automatic switch 55 is connected to this pipe 54. A pipe 56 connects the automatic switch 55 to the dead side of the motor 53 and a pipe 57 connects the switch 55 to the live side of 30 the gas motor 53.

Referring to Fig. 3 the automatic switch 55 comprises a casing 58 having a lower 35 chamber 59, a by-pass 60, an upper chamber 61, a lower pocket 62, an upper pocket 63, a valve seat 64 leading from the lower chamber 59 to the lower pocket 62, and a valve seat 65 leading from the upper chamber 61 to the upper pocket 63, the pipe 57 communicates with the pocket 62 and the pipe 56 communicates with the upper pocket 63. A diaphragm 66 is mounted against the upper end of the casing to cover the chamber 50 61, a cap 67 is screwed down upon the casing 58 to hold the diaphragm 66 in place, a spring casing 68 extends upwardly from the cap 67, a spring 69 is placed in the casing 68 against the diaphragm 66, a follower 70 is 55 placed against the upper end of the spring 69, a wall 71 closes the upper end of the spring casing, a set screw 72 is screw seated through the wall 71 against the follower 70 to regulate the tension of the spring 69 60 and a cap 73 is hinged in place to cover the set screw 72 and held by a padlock 74. A valve stem 75 is connected to the diaphragm 66 and extends downwardly through the valve seat 65, through a partition 76 between the lower pocket 62 and the upper

pocket 63 and through the valve seat 64. A valve 77 is fixed upon the valve stem 75 in position to engage the valve seat 64, and a valve 78 is fixed upon the valve stem 75 in position to engage the valve seat 64; valves 77 and 78 being located so that when the valve 77 is closed the valve 78 is open, and when the valve 78 is closed the valve 77 is open. The tension of the spring 69 is exerted to hold the valve 77 normally closed 75 so that the gas will flow from the gas chamber 18 through the pipe 54, through the valve seat 64 through the lower pocket 62 and through the pipe 57 to the live side of the gas motor 53 as required to operate the 80 motor to feed carbid to the generator, and when the gas pressure goes up the pressure will be communicated through the by-pass 60 and the upper chamber 61 to the diaphragm 66 and raise the diaphragm to open 85 the valve 77 and close the valve 78, thereby shutting off the flow of gas through the pipe 57 and stopping the motor, and then the gas will flow through the valve seat 65 and the upper pocket 63 and pipe 56 to the dead 90 side of the gas motor 53.

Referring to Fig. 4, valves 77 and 78 are incorporated into the pipes 57 and 56. A motor casing 79 has a circular chamber 80 and the shaft 52 is mounted concentric to 95 this chamber, a drum 81 is fixed upon the shaft in the chamber and winding blades 82 extend from the periphery of the drum to near the inner face of the motor casing 79. A gas dome 83 extends upwardly from 100 the motor casing 79 and a feed pipe 84 leads from the gas dome 83; there being a stop cock 85 in the feed pipe; a filling nipple 86 is tapped into the casing 79, a stop cock 87 is fixed upon the nipple and a funnel 88 105 is screwed into the stop cock so that by opening the stop cock 87 water may be poured through the funnel 88 to fill the casing 89 to the desired extent. The valves 77 and 78 hold the water in the casing, the gas 110 passing through the pipe 57 into the chamber 80 will pass upwardly through the water against the hooked sides of the blades 82 and drive the blades to rotate the shaft 52, and the shaft 52 carrying the pulley 51 will 115 drive the belt 50, the pulley 49, the shaft 46 and rotate the shaft 40 to feed the carbid from the feed plate 37 to the generating tank 1. The gas will flow from the circular chamber 80 to the gas dome 83 and through 120 the feed pipe 84 to the places of consumption. When the gas pressure in the gas dome 14 from the generator tank 1 goes above the requirements the switch 55 will operate to stop the flow through the pipe 125 57 and start the flow through the pipe 56 and the gas flowing through the pipe 56 will strike the rounded sides of the blades 82 and pass through the space 89 between the blades and the inner face of the casing 79 130

and pass upwardly through the water to the feed pipe without rotating the motor, and this operation will continue until the pressure has gone down to normal, when the 5 switch 55 will again operate to start the circulation through pipe 57 to start the motor and feed more carbid.

Various changes may be made without departing from the spirit of my invention, as 10 10 claimed.

I claim:

1. In an acetylene generator, a cylindrical casing, a shaft mounted in the casing, curved wings extending from the shaft, a gas pipe 15 connected through the bottom of the casing to discharge against the concave sides of the wings, a second gas pipe connected through the bottom of the casing to discharge against the convex sides of the wings, and a pressure 20 sure operated switch for controlling the flow of gas through said gas pipes.
2. In an acetylene generator, means for producing gas, an outlet pipe, a pressure controlled switch connected to the outlet 25 pipe, a gas operated motor, a pipe connecting the switch to the live side of the motor, a second pipe connecting the switch to the dead side of the motor, and a supply pipe leading from the motor.
- 30 3. In an acetylene generator, means for

producing gas, an outlet pipe, a pressure controlled switch connected to the outlet pipe, a gas operated motor, a pipe connecting the switch to the live side of the motor, a second pipe connecting the switch to the dead side of the motor, a supply pipe leading from the motor, means for feeding carbid to the generator, and a connection between the carbid feeder and the motor so that when the pressure is low the motor will 40 operate to feed carbid, and when the pressure goes above normal the motor will stop until the pressure goes down again.

4. In an acetylene generator, a generating tank, a gas dome extending upwardly from 45 the generating tank and in communication therewith, a pipe leading from the dome, an automatic switch connected to the pipe, two pipes leading from the automatic switch, a cylindrical casing connected to the two 50 pipes, a shaft mounted in the casing, curved wings extending from the shaft, one of said pipes being directed against the concave sides of the wings and the other one of said pipes being directed against the convex 55 sides of the wings, and the feed pipe leading from the casing.

In testimony whereof I have signed my name to this specification.

W. H. ROWE.
